UNITED STATES PATENT OFFICE

ULYSSES GRIER, OF NEW YORK, N. Y.

AEROPLANE-CLOTH SPEAKER

Application filed June 26, 1928. Serial No. 288,409.

This invention relates to aeroplane cloth radio speakers, and has among its objects the provision of a device of the character described which is of improved arrangement and construction to include an ornamental cabinet superposed over the speaker.

Another object of the invention is the provision of a device of the nature set forth, comprising an improved aeroplane cloth speaker including a diaphragm tensioned at the edges thereof and in a transverse direction at its center, for connection with a speaker unit at the center, at which region the diaphragm is re-enforced, all as hereinafter described.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

Generally described, the invention provides a loud speaker of the type well known in radio apparatus. Associated therewith is an ornamental cabinet for receiving articles of various kinds. A support is provided for the cabinet, on which support is mounted a diaphragm of aeroplane cloth secured at its edges to the support. Interiorly of the support, and to the rear of this main diaphragm is an auxiliary smaller diaphragm of aeroplane cloth. The diaphragms are tensioned transversely thereof and in opposite directions. They have central openings to permit engagement therewith of a loud speaker unit. At the openings referred to, particularly in conjunction with the main diaphragm, is a re-enforcement of aeroplane cloth, while metallic washers engage the diaphragms at said openings and externally of the re-enforcement. These washers are perforated to permit an adhesive to be passed therethrough to cement together the fabric portions to strengthen the diaphragms, and particularly the main diaphragm to prevent

a break in the diaphragm from initiating at the opening thereof.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

In the drawings:

Figure 1 is a front elevation showing a device embodying the invention.

Fig. 2 is a rear elevation thereof.

Fig. 3 is a vertical section taken on the line 3—3 of Fig. 2.

Fig. 4 is a sectional detail view showing features of the invention.

Fig. 5 is a view of a detail of the invention.

Referring in detail to the drawing, 10 denotes a device embodying the invention. The same is seen to include actuating means, such as a loud speaker 11 of the type that is commonly used in radio apparatus. Superposed upon the loud speaker is a cabinet 12. The latter may be of any suitable design, and while the upper portion 13 thereof is shown as being of triangular form, nevertheless the same may also be semi-cylindrical, hemispherical, or of any other desired conformation according to the desires or tastes of the user.

The cabinet 12 comprises a door 14 hingedly mounted at 15 and retained in closed position by any suitable locking device 16. The said door is of a shape in conformity with that of the body of the cabinet and includes preferably a glass pane 17 through which various ornamental and decorative articles 18 are positioned on a base 19 and a shelf 20 may be visible. It will be appreciated that the articles 18 may be of various designs and includes chinaware, silverware, and any of the various objects that are usually placed in

ornamental closets to be visible through transparent walls or windows therein.

Supporting the cabinet 12 is a base 21, the same including side members 22 coacting with the shelf 19 at their upper ends and with a cross bar 23 at their lower end. On the base 21 is mounted the main speaker diaphragm 24, this being stretched taut across the front of the base and being secured to the edges of the base in any suitable manner as, for example, by tacks or screws 25 passing through the diaphragm and into the adjacent portions of the base. As may be noted in the drawing, the diaphragm 24 is inwardly deflected centrally under tension with mechanism hereinafter described and disposed within the base 21 to the rear of the said diaphragm. The latter provides a very large vibrating surface, insuring ample volume and since it extends substantially across the entire front of the base of the device, it is in practice suitably ornamented by pictures or the like that may be drawn or painted thereon. By placing slats 26 along the edges 25 of the base 21 to conceal the edges of the diaphragm 24 and the heads of the tacks 25, a suitable finished external appearance is assured.

To the rear of the diaphragm 24 are mounted a pair of cross bars 27 vertically spaced from one another and in the same vertical plane preferably in parallelism with that of the diaphragm 24. These bars 27 form a rigid frame across which is stretched taut a small auxiliary diaphragm 28, the same being secured to the frame in any suitable manner and preferably by means of tacks or screws 29 passing through the edge portions of the diaphragm 28 and into the bars 27.

The auxiliary diaphragm 28 is tensioned in an opposite direction relative to the main diaphragm 24 with the result that the two diaphragms are in relatively close proximity to each other at the central portions of each. By this arrangement a loud speaker unit 30 of any conventional well known type in the radio art may have connection by means of a pin 31 with the main diaphragm 24 and in such manner as to insure sufficient tautness in the latter and particularly at the central region thereof.

The loud speaker 30 may be mounted in any feasible manner as, for example, by means of brackets 32 which may be engaged with screws, or the like, to the parallel bars 33 that are fixed to the side members 22 of the base. The lead 34 of the loud speaker may be extended through either one of the two openings 35 provided in the side members 22 of the base. Accordingly the lead 34 may be conveniently connected with the receiving set regardless of the relation of the device 10 thereto.

The material of which the diaphragms 24 and 28 consist is preferably a fabric as, for

example, aeroplane cloth which is of sufficiently close and uniform weave and ample strength to satisfy all requirements. In conjunction with the aeroplane cloth is employed a liquid material which may be in the nature of an adhesive, or the like, and which has the effect of causing a uniform contraction in the cloth and also imparting thereto a stiffness so that the diaphragms are rendered as resonant as those on a drum. In constructing a device according to this invention, it is essential that the liquid referred to be applied according to a predetermined plan and with sufficient rapidity to cause a uniform action thereof in all parts of the cloth so as to prevent in the finished diaphragm a warped effect and to prevent the possible uneven strains that might otherwise be created from causing the diaphragm to break.

In constructing a device made according to this invention after the diaphragms 24 and 28 have been nailed to their corresponding frames or supports with a fair degree of tautness, the said diaphragms are centrally drawn together and a clamping device 36 passed through openings 37 and 38 in the diaphragms to secure the pin 31 therewith. The clamping device 36 is seen to comprise a plurality of washers or plates 39 and 40 coacting respectively with the diaphragms 24 and 28 and serving to strongly clamp the central portions thereof together. Thereafter a thumb screw 41 of the clamping device or any other suitable means that may be provided may be used to obtain the firm contact between the pin 31 and the clamping device.

After the aforesaid preliminary steps in the manufacture of the instrument have been completed, the liquid is used on the edge portions of the main diaphragm 24 and over the heads of the nails, this being done before the slats 26 have been put in place. Accordingly the diaphragm is strengthened and stiffened to the point where the heads of the nails will not pull through the diaphragm when the liquid is thereafter applied to the other portions thereof. The liquid is then rapidly and by means of a brush applied over all the remaining parts of the main diaphragm 24, causing the same to become extremely taut as soon as the liquid has dried which takes place within a few minutes. The same process is repeated for the diaphragm 28. Accordingly a certain balance is obtained and a high degree of tension which insures an excellent vibrating character in the main diaphragm. A plurality of coats of the liquid may be applied, but if too many coats of the liquid are used the tension upon the diaphragm may become so high as to cause the same to break. In practice it is found that breakage is most liable to occur at the central portion of the main diaphragm, since the central portion is provided with an opening, and, furthermore, the tension is really

highest per unit area at the center of the diaphragm. Therefore when breakage occurs, it usually begins at the opening 37. I therefore prefer to employ a fabric reinforcement 43 which may likewise consist of 5 aeroplane cloth and is cut in the form of a disk and centrally perforated at 44 to receive the clamping device 36. Since the said re-enforcement is to the rear of the sounding diaphragm, it will not be seen and therefore 10 will not affect the external appearance of the machine. The re-enforcement 43 may extend beyond the edges of the washer 39 and a backing plate 45 may be provided for 15 the re-enforcement to hold the same in snug contact with the sounding diaphragm 24. The washer 39 is perforated by means of a plurality of holes 46 and likewise the plate 45 is perforated in proximity to the periphery 20 thereof by holes 47. The liquid may therefore be applied through the perforations 46 and 47 to reach the central portion of the sounding diaphragm that is otherwise inaccessibly retained between the washers 39 25 and 40. Therefore the said central portion is suitably strengthened and at the same time the re-enforcement 43 will be caused to strongly adhere thereto so that the possibility of breakage of the sounding diaphragm is 30 greatly diminished. Likewise the washer 40 may be perforated in the same manner as that shown for the washer 39 and the liquid applied through the perforations to the central portion of the auxiliary diaphragm 28.

35 After the device has been thus completed, it may be painted properly and the painting may include the formation of any designs that may be deemed desirable.

It is thus seen that I have provided a 40 device that fulfills the several objects of the invention and is well adapted to meet the conditions of practical use.

I claim:

1. A device of the character described, including a cabinet, supporting means for the cabinet including a pair of side members, a main diaphragm of aeroplane cloth mounted at its edges on said side members and at its upper and lower ends on said cabinet, an auxiliary diaphragm to the rear of the main diaphragm, said main and auxiliary diaphragms being centrally perforated and connected together, and tensioned in opposite directions at the center, and being both stretched taut, 50 along the elements thereof, and means to transmit sound vibrations to the main diaphragm passing through the perforations in the diaphragms and engaging the same, there being a small fabric re-enforcement 55 cemented to the main diaphragm about its perforation, said means including a pair of washers disposed at opposite sides of the diaphragms to clamp the same together and afford strong engagement therewith, said 60 washers being perforated to permit the ap-

plication of liquid cement therethrough to strengthen the diaphragms and to cement said re-enforcement to the main diaphragm as aforesaid.

2. A device of the character described, including a diaphragm of aeroplane cloth, means to transmit sound vibrations to said diaphragm, and means to engage said diaphragm along the edges thereof to stretch same taut, said diaphragm being centrally 70 perforated to permit the connecting means to engage the same, a piece of re-enforcement fabric for the diaphragm about said perforation, the connecting means including washers on opposite sides of said diaphragm, one 75 of said washers being perforated to permit a liquid cement to be passed through the washer perforations to cement the re-enforcement to the diaphragm.

In testimony whereof I affix my signature. 80

ULYSSES GRIER.
